I claim the ornamental design for an electric toothbrush charger, as shown and described.

DESCRIPTION

FIG. 1 is a front perspective view of an electric toothbrush charger of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken line showing of electric toothbrush charger is included for the purpose of illustrating environment and forms no part of the claimed design. Additionally, the unevenly broken lines in the drawings define the limits of the claimed design.
